UNITED STATES PATENT OFFICE.

ALVIN G. PORTER, OF AUBURN, WASHINGTON.

PAPER RECEPTACLE.

1,303,723.

Specification of Letters Patent. Patented May 13, 1919.

Application filed January 10, 1919. Serial No. 270,554.

To all whom it may concern:

Be it known that I, ALVIN G. PORTER, a citizen of Canada, residing at Auburn, in the county of King and State of Washington, have invented new and useful Improvements 5 in Paper Receptacles, of which the following is a specification.

This invention relates to new and useful improvements in receptacles made from paper or like material and the principal 10 object of the invention relates to the manner in which the parts of the receptacle are held together.

With the above and other objects in view 15 the improvement resides in the construction, combination and arrangement of parts set forth in the following specification and falling within the scope of the appended claim.

In the drawing:

20 Figure 1 is a view of a box, in partly assembled position, made in accordance with my invention,

Fig. 2 is a bottom view of the completed box, and

25 Fig. 3 is a perspective view of a bottle made in accordance with my invention.

This invention is an improvement over that for which I have been granted Letters Patent of the United States on September 9, 30 1913, No. 1,072,987.

As shown in the drawing the box is made from one piece of material. The box is composed of the sides 1 and the bottom 2. The bottom is composed of triangular-shaped extensions of the sides with the material scored at the base of the triangle so as to facilitate the folding of the bottom pieces at right angles to the sides. The free edges of each bottom piece is also scored so as to produce 35 flaps 3 and a V-shaped recess is cut from one flap at the apex of the bottom piece so that one flap is longer than the other so as to produce an extension 4. It will be seen that the long flaps on each pair of bottom pieces are 40 opposite each other so that when the bottom pieces are bent over these long flaps will

contact with each other and the long flaps of one pair of end pieces are directly opposite the long flaps of the other pair of end pieces so that the extensions 4 will overlap in the 50 middle of the bottom with the ends of the short flaps abutting them. The flaps are held together by passing staples 6 there-through and through the extensions or said flaps may be secured together by any other 55 suitable means.

The meeting ends of the sides of the box may be secured together by the staples 7 or by any other suitable means.

The box may be formed into an egg box by 60 placing the usual partition strips therein or said box may be used for berries or in any desired way.

The bottle shown in Fig. 3 has its bottom made similar to the box just described and 65 the top of the bottle is closed by pressing two opposite sides inwardly and then bringing the other two sides together at their edges and passing a clip 8 around the same. In other respects this bottle is similar to that 70 described in the beforementioned patent.

From the above description taken in connection with the accompanying drawing, the simplicity and advantages of the improvement will, it is thought, be perfectly apparent to those skilled in the art to which 75 such invention appertains without further detailed description.

Having thus described the invention, what I claim is:

80 A receptacle of the class described made from a single sheet of material and having its bottom composed of triangular-shaped extensions of the sides, each extension being scored adjacent its free edges to form flaps 85 and one flap having a cut-out portion therein at the apex of said extension so as to provide an extended portion on the other flap, and means for securing said flaps and extended portions together.

90 In testimony whereof I affix my signature.
ALVIN G. PORTER.
